Attorney

UNITED STATES PATENT OFFICE.

ANTHONY G. JACKSON, OF PHILADELPHIA, PENNSYLVANIA.

CRANK-CASE REINFORCEMENT OR REPAIR ARM.

1,332,840.

Specification of Letters Patent.

Patented Mar. 2, 1920.

Application filed July 29, 1918, Serial No. 247,272. Renewed January 13, 1920. Serial No. 351,254.

To all whom it may concern:

Be it known that I, ANTHONY G. JACKSON, a citizen of the United States, residing at Philadelphia, in the county of Philadelphia and State of Pennsylvania, have invented certain new and useful Improvements in Crank- Case Reinforcements or Repair Arms, and do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in crank case repair arms for engines of different types, such as the Ford, Hudson, etc., and consists of a simple and efficient device which may be applied without the use of special tools, welding or brazing, etc., and which may be easily and quickly attached without the necessity of sending the engine to a factory, where special tools are required, as is the custom with repair arms now commonly constructed.

The invention comprises various details of construction, combinations and arrangements of parts which will be hereinafter fully described, shown in the accompanying drawings and then specifically defined in the appended claims.

My invention is illustrated in the accompanying drawings which, with the letters of reference marked thereon, form a part of this application and in which:

Figure 1 is a vertical sectional view, showing the application of my invention to the crank case of an engine of the Ford type, and

Fig. 2 is a detailed perspective view of the crank repair arm.

Reference now being had to the details of the drawings by letter:

45 A designates the crank case of an engine, having a laterally extending portion B, and C is a block over which an angled portion D of the lateral projection of the crank case bears. Angled plates E are bolted, or otherwise fastened, to the block C, and are provided with upright inclined portions F which are riveted, or otherwise securely fastened to the angle plate H, the wing H' of which is adapted to rest upon the horizontal flange K of the chassis K'. The inclined portion of said angle plate has an upright

70 arm P, which is riveted, or otherwise secured, to the inclined portion of the angle plate H and is provided with an aperture R through which a bolt passes and which bolt 60 also passes through the apertured portion of the chassis and forming means for securely holding the angle plate to the latter. The upper end of the arm P, it will be noted, bears against the upper horizontal flanged 65 portion of the chassis. The lower ends of the plates D are apertured as at T to receive bolts or screws which are passed through the same and the block C upon which the crank case of the engine rests.

75 By the provision of a repair arm made in accordance with my invention, it will be noted that a convenient means is provided for repairing engines and trucks of different kinds and one which may be easily and 80 quickly adapted to the crank case of a chassis, without the necessity of welding or brazing, but simply by the employment of bolts, and at a minimum of time and labor.

85 By way of illustration, repair of a Ford car by my improvements will be described. In the Ford car the bracket which supports the crank case A from the chassis frame K', is riveted to the crank case below the flanges B thereof and has an upwardly extending 85 arm passing between the flanges B and the chassis frame, such arm having at its top a lateral extension which rests upon the top leg of the chassis frame and is secured thereto. This bracket usually breaks in the 90 arm portion thereof at a point adjacent the flanges. In making the repair the upper portion of the bracket secured to the chassis frame is removed and my improved bracket substituted therefor, this being possible by 95 reason of the fact that the arms F are spaced apart so as to straddle the remaining portion of the original bracket which is riveted to the crank case. The arms F are spaced at such a distance that the apertures T will 100 align with the bolt holes in the flanges B of the crank case which receive the bolts securing the halves of the crank case together. The angle H supports the crank case against downward movement and the 105 plate P and the bolt passing through aperture R support the parts against upward movement and against lateral displacement relative to the frame.

110 In using my bracket as a reinforcement; i. e., before the original bracket has broken, I remove the bolts which fasten the bracket

to the chassis frame, slip my improved bracket in position with the arms F, straddle the original bracket and then bolt both the original bracket and the reinforcement bracket in place. One of the particular advantages of my invention is that by my construction of bracket engaging the inner portions of the chassis frame, I am enabled to use the same bracket either as a repair or as a reinforcement, whereas in analogous devices in the art, it is necessary to use one style of bracket for a reinforcement and another style of bracket for a repair.

What I claim to be new is:

15. 1. A reinforcement or repair arm for engines of automobiles, comprising in combination with the chassis, an angle plate rest-

ing upon an inner laterally extending flange of the chassis, angle arms riveted to said angle plate and adapted to be bolted to a 20 block upon which the crank case rests.

2. A reinforcement or repair arm for engines of automobiles, comprising in combination with the chassis, an angle plate resting upon a laterally extending flange thereof, angle arms adapted to be secured to the crank case of the engine, a member bolted to the angle plate and to said chassis.

In testimony whereof I hereunto affix my signature in presence of two witnesses.

ANTHONY G. JACKSON.
